UNITED STATES PATENT OFFICE.

JAMES L. SEAVER, OF ST. LOUIS, MISSOURI.

LATCH.

Application filed February 1, 1921. Serial No. 441,547.

To all whom it may concern:

Be it known that I, JAMES L. SEAVER, a citizen of the United States, residing at St. Louis, Missouri, have invented a certain new and useful Improvement in Latches, of which the following is a full, clear, and exact description, such as will enable others skilled in the art to which it appertains to make and use the same, reference being had to the accompanying drawings, forming part of this specification.

This invention relates generally to latches and more particularly to mortise door latches. The principal objects of my invention are to provide an improved door latch having all of its operating parts contained in a housing so that there are no outwardly projecting parts such as door knobs and to provide escutcheon plates for said latch having hand openings and suitable closure means therefor.

Further objects of the invention are to provide a latch which can be manually operated without the use of knobs or other outwardly projecting means and to provide means for normally shutting off access to said latch, which means can be easily manipulated to provide access to said latch when it is desired to operate the same.

Still another object is generally to improve upon and simplify the construction of door latches which latches are of simple and durable construction and efficient in operation.

In the drawings,

Figure 1 is a fragmental view of a door equipped with my improved latch.

Figure 2 is a horizontal cross section taken on the line 2—2 of Figure 1.

Figure 3 is a fragmental view of the inner side of one of the escutcheon plates and shows means for closing the hand opening therein.

Figure 4 is a detail view of a plate forming the side wall of the latch housing.

Figure 5 is a perspective detail view of a frame carrying the latch bar.

Figure 6 is a vertical cross section through a door showing the latch in position therein

and one side wall of the latch housing being removed to better illustrate the invention.

Figure 7 is a vertical cross section taken on the line 7—7 of Figure 6.

Referring by numerals to the accompanying drawings, A represents a door equipped with my improved latch and provided on each side with escutcheon plates 10. The operating mechanism is contained in a rectangular housing 11 having a side wall 12, horizontally projecting top wall 13, bottom wall 14, and intermediate wall 15, and a rear end wall 16. The front portion of the housing 11 is closed by a surface plate 17 having ears or lugs 18 which are fixed to housing 11 by rivets 19. The surface plate 17 is counter-sunk in the edge of the door in the usual manner and is secured in position by means of wood screws 20. Top wall 13 and intermediate wall 15 are provided with depending lugs 13^a and 15^a, respectively, which have threaded engagement with screws 21.

A plate 22 is held in position on housing 11 by screws 21 and forms the other side wall of said housing. Inwardly presented horizontal flanges 23 are formed integral with plate 22 and their front ends are joined by a vertical flange 24 while their rear ends are open. A rectangular frame 25 is slidably mounted on said flanges, its upper transverse member resting on the upper horizontal flange 23, and its lower transverse member resting on intermediate wall 15, the length of said transverse members being greater than the length of horizontal flanges 23 so that there is a clearance between frame 25 and flanges 23 which permits of horizontal movement of said frame.

To the front wall of frame 25 is secured a latch bar 26 which operates through a suitable opening in surface plate 17. Frame 25 and latch bar 26 are yieldingly held in projected position by a leaf spring 27, one end of which is anchored to housing 11 while its free end bears against frame 25. Side wall 12 of housing 11 is provided with an opening 12^a and plate 22 is provided with a similar opening 22^a.

The escutcheon plates 10 are provided with openings 10^a which coincide with openings 12^a and 22^a. These openings provide access to frame 25 in housing 11 so that a person can insert his hand through said openings into said housing and operate latch bar 26 by applying manual pressure on the rear wall of frame 25, overcoming the resistance of spring 27, thereby moving said frame 25 rearwardly and withdrawing latch bar 26. The openings 10^a in plates 10 are normally held closed by doors 28 hinged to the inner sides of the escutcheon plates 10 by means of rods 29.

15 A coiled spring 30 on rod 29 yieldingly maintains each door in closed position.

When the lock is in assembled position, plate 22 is secured to housing 11 by means of screws 21 and rectangular frame 25 occupies an outer position on frames 23 and 24 and is held against vertical movement by lug 13^a, intermediate wall 15, and flanges 23. The rear end of flanges 23 terminating short of the rear wall of frame 25, the latter 25 is capable of horizontal movement a sufficient distance to move latch bar 26 forwardly under the influence of spring 27 into operative or projected position.

When pressure is manually applied to the 30 rear wall of frame 25, the latter is moved rearwardly against the influence of spring 27 and latch bar 26 is retracted within housing 11, as shown in full lines in Figure 5. Vertical flange 24 against which frame 25 abuts when in a retracted position, limits the rearward movement of said frame. As soon as the manual pressure is removed from frame 25, spring 27 will move said frame and latch bar 26 into a projected 40 position, as shown in full lines in Figure 2 and in dotted lines in Figure 5.

In closing the door, the inclined face on latch bar 26 causes bar 26 and frame 25 to move inwardly until latch bar 26 enters the 45 latch bar recess in the door jamb when spring 27 will move frame 25 and latch bar 26 into a projected position.

Door A is mortised in the usual manner to receive the latch and the escutcheon plates 50 are held in position on said door in any suitable manner and preferably by screws 48, the heads of which are seated in the inner plate and have threaded ends which screw into sockets 49, non-rotatably seated 55 in the outer plate.

A latch of my improved construction has no projecting parts such as knobs which might mar the walls or present unsightly appearance, and can be easily applied in position 60 with ordinary tools and in the usual manner.

Obviously various changes and arrangements of parts in my improved latch can be made and substituted for those described and shown, without departing from the 65 spirit of the invention.

I claim:

1. In a door latch of the class described, a housing provided with oppositely disposed hand openings, a rectangular frame slidably mounted in said housing and adapted to be manually operated through said hand openings and a latch bar fixed to said flange and designed when retracted to occupy a position wholly within said housing.

2. In a latch of the class described, a housing provided with hand openings, a latch bar slidably mounted in said housing and adapted to be manually operated through said hand openings, and means for closing said hand openings.

3. In a latch of the class described, a housing provided with hand openings, a latch bar slidably mounted in said housing and adapted to be manually operated through said hand openings, and yielding closure means for said hand openings.

4. In a latch of the class described, a housing, a latch frame slidably mounted therein, a latch bar carried by said latch frame, said latch frame and said latch bar being yieldingly held in projected position and adapted to be manually engaged and moved in retracted position, and yielding closure means normally shutting off access to said latch frame.

5. In a latch of the class described, a housing provided with hand openings, a manually operable latch bar slidably mounted in said housing, escutcheon plates provided with hand openings which coincide with the openings in said housing, and closure means for the hand openings in said escutcheon plates.

6. In a latch of the class described, a housing provided with hand openings, a manually operable latch bar slidably mounted in said housing, escutcheon plates provided with hand openings which coincide with the openings in said housing, and closure means hinged to the inner sides of said plates and adapted to close the openings in said escutcheon plates.

7. In a latch of the class described, a housing provided with hand openings, a manually operable rectangular frame slidably mounted in said housing, a latch bar fixed to said frame, a spring engaging said frame to yieldingly hold said latch bar in projected position, escutcheon plates having hand openings, and closure members hinged to the inner sides of said plates and closing the openings therein.

8. The combination with a door provided with a latch, of escutcheon plates having hand openings for manually operating said latch, and means for closing the openings in said plates.

9. The combination with a door provided with a latch, of escutcheon plates provided with hand openings for manually operating

said latch, and closure members for said openings and hinged to the inner sides of said plates.

10. A door latch comprising a housing open at one side, a plate for closing the open side of said housing and provided with inwardly projecting flanges, a rectangular

frame slidably mounted on said flanges, and a latch bar fixed to said frame and adapted to project outwardly through said housing. 10

In testimony whereof I hereunto affix my signature this 29th day of January, 1921.

JAMES L. SEAVER.
